UNITED STATES PATENT OFFICE

DELBERT CLINE, OF NEWCASTLE, INDIANA, ASSIGNOR TO JESSE FRENCH & SONS PIANO COMPANY, OF NEWCASTLE, INDIANA, A CORPORATION OF INDIANA

DESIGN FOR A RADIOCABINET

Application filed December 3, 1930. Serial No. 37,870. Term of patent 3½ years.

To all whom it may concern:

Be it known that I, DELBERT CLINE, a citizen of the United States, residing at Newcastle, in the county of Henry and State of Indiana, have invented a new, original, and ornamental Design for Radiocabinets, of which the following is a specification, reference being made to the accompanying drawing, forming part thereof.

The figure is a perspective view of a radiocabinet, showing my new design, the two opposite lateral sides of the cabinet are identical and the rear side is plain.

I claim:

The ornamental design for a radiocabinet, as shown and described.

In testimony whereof I affix my signature.

DELBERT CLINE.
